ARRANGEMENT FOR TREATING METAL PARTS

Erwin Bührer, Schaffhausen, Switzerland, assignor to Georg Fischer Aktiengesellschaft, Schaffhausen, Switzerland, a company of Switzerland

Application October 3, 1950, Serial No. 188,139
In Switzerland October 12, 1949

1 Claim. (Cl. 51—164)

1

The present invention relates to an arrangement for the treatment of metal parts in drums or barrels which, during their movement through the space in which the goods being treated are subjected to the action of a liquid substance, are rotated about a horizontal axis. Arrangements of this type are employed more particularly for pickling and otherwise pretreating iron parts which, subsequently to this treatment, are to be provided with a metal coating, e. g. a coating of zinc. The primary aim achieved by the rotation of the drum is to wet with certainty all the interior and exterior surfaces of the metal parts charged therewith. It is known practice to move about, in a treatment bath, barrels charged with metal parts, in order to encompass as intense and active as possible a change of the liquid treatment medium within the barrels themselves. Such arrangements are known under the name of rocker-type pickling baths.

The present invention differs from known arrangements for the treatment of metal parts in barrels in that the barrel is suspended on ropes the ends of which are attached to a swinging double lever.

In the drawings,

Fig. 1 a lateral elevation of an embodiment of the invention;

Fig. 2 a section along the line II—II in Fig. 1.

Figs. 1 and 2 illustrate a tank or vat 1 filled with a liquid 2. A cylindrical drum or barrel 3 accommodates the metal parts 4 to be treated. The barrel 3 is provided at its ends with two grooves 5 serving as guides for two steel ropes 6 whose ends 7 and 8 are secured to a two-armed lever 10 with arms of unequal length pivotingly arranged on a shaft 9. The shaft 9 of the two-armed lever 10 is supported in two bearing brackets 11. A further arm 12 is secured to the two-armed lever 10, which arm 12 is acted upon by the connecting rod 13. The motor 14 produces the pivoting motion of the two-armed lever 10 through the agency of a crank 15. 16 is the crank-bearing of the connecting rod 13.

The manner in which the described arrangement functions will now be explained in reference to the drawing: the connecting rod 13 is given a reciprocating motion by the motor 14 with the result that it pivots the two-armed lever 10 through an angle of approximately 90°. 50 In Fig. 1 the end position of the two-armed lever is partly indicated by the discontinuous outline of the end 8. The dimension arrow 17 shows the stroke or travel described by the end 8 of the steel rope 6 during the reciprocating motion. 55 The end 7 of the steel rope 6 performs a shorter

stroke or travel 18. The axis of the barrel 3 is raised by half the difference between the strokes 17 and 18, and lowered again. In Fig. 1 the movement of the barrel is represented by the dimension arrow 19.

To charge and discharge the barrel 3, the latter is lifted out of the bath 2. The embodiment shown in Figs. 1 and 2 of an arrangement for treating metal parts may be built and used in multiple type without altering the principle. In this event it is possible, for instance, to arrange a plurality of barrels on a conveyor system of the roundabout type with a view to stage-by-stage treatment of the contents of the barrels.

15 The inventive idea includes a provision of double levers having arms of unequal lengths to provide a rotary movement simultaneously with a reciprocating movement of the drum. The rotary movement imparted to the barrel provides for a thorough netting of all the metal parts and causes complete removal of the occluded air bubbles and of the gases which arise during pickling. The rotary motion also renders possible complete discharge of the barrel when it is lifted clear of the bath. The displacement of the axis 20 of the barrel in the course of the reciprocating movement produces a more vigorous change of liquid treatment medium within the barrel.

25 The embodiments illustrated do not exhaust the possibilities of the inventive idea; other constructions are conceivable for producing the simultaneous rotary and reciprocating motion of the barrel.

30 What I claim is:

35 A device for treating metal parts, said device comprising in combination with a tank for a treating liquid and a drum for said metal parts, ropes suspending said drum within said tank, a lever pivoted intermediate its ends and having two arms of unequal length, said ropes being attached to said ends, and means connected with said lever for swinging the same about its pivot.

ERWIN BÜHRER.
